(57) **CLAIM**

The ornamental design for a disc brake calliper, as shown and described.

DESCRIPTION

FIG. 1 is a perspective view of a disc brake calliper showing our new design;

FIG. 2 is a perspective view thereof from an end opposite that of FIG. 1;

FIG. 3 is another perspective thereof;

FIG. 4 is another perspective view thereof from an end opposite that of FIG. 3;

FIG. 5 is a side view thereof;

FIG. 6 is a side view thereof, from a side opposite that of FIG. 5;

FIG. 7 is an end view thereof;

FIG. 8 is an end view thereof from an end opposite that of FIG. 7; and,

FIG. 9 is a top view thereof.

The broken lines illustrate portions of the disc brake calliper that form no part of the claimed design.

1 Claim, 9 Drawing Sheets(56)
